UNITED STATES PATENT OFFICE.

SAMUEL M. LANGSTON, OF WENONAH, NEW JERSEY.

METHOD OF MAKING SHINGLE STRIPS.

Application filed May 31, 1922. Serial No. 564,682.

To all whom it may concern:

Be it known that I, SAMUEL M. LANGSTON, a citizen of the United States, and resident of Wenonah, in the county of Gloucester and State of New Jersey, have invented certain new and useful Improvements in Methods of Making Shingle Strips, of which the following is a specification.

This invention relates to the manufacture of that type of multiple shingle or roofing strip which is made of paper, felt, asbestos, or other analogous flexible sheet material saturated or treated with asphalt, tar, pitch or other waterproofing composition and coated on at least one surface with sand, grit, crushed slate, or other mineral or fire-proof material.

A common form of such multiple shingle is of a length several times the width and provided with a plurality of notches or recesses in one of the longer edges, so as to form tabs each of a width corresponding to that of an individual shingle. The strips when laid in overlapping rows on the roof have the tabs and notches exposed at the lower edge to give the general appearance of individual shingles with narrow spaces therebetween, as in the ordinary wooden shingle roof.

The notches should be positioned in each strip so that a notch of the proper width will be formed between adjacent shingle tabs at the abutting ends of two strips. The strips may be symmetrical and each have a notch at each end thereof and of a width equal to only one half the width of the other notches or recesses in the strip or the strips may be non-symmetrical and have the notch at one end of the strip of the full width of the other notches in the longitudinal edge but with no notch at the other end. It is customary to cut such strips from sheet material which is continuously or intermittently fed from a roll, a saturating and coating machine, or other source of supply.

By means of my invention I produce shingle strips of the second mentioned type, that is, non-symmetrical strips in which one shingle simulating portion or tab has its side edge in alignment with the end of the strip, and the strip has a full width notch or recess opening out at its opposite end.

In carrying out my invention strips of this character are formed by slotting or

perforating a sheet or blank of a width substantially equal to a multiple of the width of the finished strip, and separately cutting the sheet transversely and longitudinally, the distance between the transverse cuts being equal to the length of the finished strips and the distance between the longitudinal cuts being equal to the width of the finished strips, the slots or perforations having been so positioned as to form the slots or notches in said finished strips. The cutting of the sheet transversely into sections and the slitting of the separate sections longitudinally into the strips, whereby the strips extend lengthwise of the sheet, has many advantages, as pointed out in my Patent No. 1,441,359, granted January 9, 1923. Among these are the more rapid formation of the complete strips by reason of the fewer transverse cuts; causing variation in the width of the sheet to appear in the strips as unobjectionable variations in strip width rather than objectionable variations in strip length, the avoiding of tabs or projecting shoulders which may catch on parts of the machine as the sheet advances; and the more economical utilization of the sheet if the sheet be much wider than the desired length of a strip.

From the standpoint of simplicity of the machine it is important that the transverse cuts be along straight lines extending the full width of the sheet, whereby either a plurality of the finished strips are severed from the body of the slotted sheet by a single straight line cut, or the sheet is severed into sections which are later cut lengthwise into finished strips.

The shingle strips as laid in forming a roof, have the ends of the tabs or individual shingle portions exposed, while the opposite edge of each strip is concealed beneath the strip or strips of the next row. As the original edges of the sheet are often somewhat irregular, it is desirable that said original edges form the non-slotted or concealed edge of the strip rather than the edge of the strip formed by the ends of the tabs which are exposed in use, whereby all of the exposed edges are accurately cut and uniformity and regularity of appearance is produced.

In laying the roof it is also important that the strips all have their end recesses at the same end, in other words, the strips

cannot be properly assembled to produce uniformity of appearance if some have the end recesses at one end and some at the other.

The main object of my invention is to cut sheet material into non-symmetrical strips of the character above described, all of exactly the same shape with the strips extending lengthwise of the sheet, and with all of those edges of the strips which are exposed in use formed by accurately positioned cuts, as distinguished from the original edges of the sheet, and with all of the transverse cuts along straight lines extending the full width of the sheet. I secure this object by a novel arrangement or placing of the slots or perforations in the sheet whereby all of the slots are between and spaced from the side edges of the sheet, and each transverse cut coincides with one side edge of a slot in one row and with the opposite side edge of a slot in another row. Thus the strips which have their slots opening or facing toward one side edge of the sheet have their end slots formed at the advancing end of the strips while the strips which have their slots opening or facing toward the opposite side edge of the sheet have their end slots at the opposite end of the strips and all of the strips will be of the same shape and size.

So far as my present invention is concerned the sheet after being slotted or perforated may be slit into strips and thereafter these strips cut off transversely into sections, or the sheet may be cut into sections and each section thereafter slit lengthwise, or the slitting of the sheet into strips may be done before the slotting or perforating. Preferably I operate in accordance with the method claimed in my patent above referred to, and first form the slots or perforations, then cut the sheet transversely into sections and thereafter slit or longitudinally cut each section into the final strips, whereby the various advantages set forth in said application are secured.

In the accompanying drawings:

Fig. 1 is a diagrammatic view of machine parts which may be employed and properly driven and timed in respect to each other to carry out my improved method.

Fig. 2 is a plan view of a sheet, successive portions from the right hand end toward the left hand end showing the action of the successive steps of the method, and

Figs. 3, 4 and 5 are plan views of sections of a sheet with other arrangements of the openings and cuts.

The material employed in carrying out my improved method may be that commonly employed in the manufacture of multiple shingles or roofing strips. This material is illustrated as a continuous sheet A which may be delivered in the direction of the arrow from a roll or from a machine employed

for saturating, coating or otherwise treating the body or material of the sheet. This sheet may be of a width substantially equal to two, three, four or more strips, that illustrated in Fig. 2 being of a width equal to four times the width of a single complete shingle strip. Obviously if the sheet be other than substantially a multiple of a width of the strip, the edge portion may be trimmed off at the time the strips are separated by the longitudinal cutting apparatus.

As the first step in the cutting process there are formed a plurality of rows of transversely extending slots, the rows extending lengthwise of the sheet and the slots being uniformly spaced in all of the rows. The slots in one or more of the rows are offset in the direction of the length of the sheet from the slots in the other rows and to an extent equal to the width of the slot. As shown in Fig. 2, there are two rows of slots B, the slots of each row being in alignment transversely of the sheet with those of the other row. There are also two rows of similar slots B', the slots of one row being in alignment transversely of the sheet with the slots of the other row, but each of the slots B' has one of its side edges in alignment transversely of the sheet with a similar edge of a slot B' in the other row, and with the opposite edges of slots B in the two first mentioned rows. Thus, if the sheet be cut transversely on such a line C-C, the slots B will lie at one side of the line and the slots B' at the opposite side of the line, and all four slots will open out at the resulting cutting edges. The distance between the transverse cuts may correspond to any desired number of individual shingle portions which it is desired to include in an individual shingle strip. The sheet may be cut into sections D by the transverse cuts each so positioned as to intersect all of the slots of a transverse row and coincide with one edge of one or more of the slots, and with the opposite edge of the other slots in said row. The sections D may be thereafter slit or cut lengthwise into the final individual shingle strips E.

The longitudinal cuts are along lines which coincide with the ends of the slots in the several rows so as to form tabs or individual shingle portions F with intervening notches G opening at but one longitudinal edge of the sheet. It will be noted that each strip has a tab, or shingle portion F' which has its side edge in alignment with an end edge of the strip, and has a notch G' at the opposite end of the strip which opens out not only at the side of the sheet but at the end. By means of my arrangement of slots each one of the strips E, which has the tabs F facing toward one original edge of the sheet, has its notch G' at one end, while each of the strips which have their tabs facing toward the opposite

original edge of the sheet has its notches G' at the opposite end. Thus all of the strips are exactly the same as to size and shape.

In Fig. 2 I have shown an arrangement of 5 strips whereby the two strips at one side of the center have their tabs facing toward the opposite original edge of the sheet, and those on the other side of the center line extending the other way. Thus, each one of the longitudinal cuts registers with the ends of the slots in at least one of the rows.

In Fig. 3 I have shown a slightly different arrangement in which alternate strips have their tabs facing in opposite directions and 15 the cut along the center line of the sheet separates the two middle strips but does not register with the slots in any of the rows.

In Fig. 4 three strips face one way and the fourth the opposite way.

20 If the sheet be of such width as to form only three strips, these may be arranged as shown in Fig. 5, while if the strip be of a width substantially equal to only two strips, then these strips might be arranged similar 25 to the upper two in Figs. 3, 4 or 5, or the middle two of Fig. 2.

The apparatus for carrying out my improved process forms no portion of my present invention. A form of apparatus which 30 may be employed for carrying out the process hereinafter claimed is disclosed and claimed in my copending application, Serial No. 578,172, filed July 28th, 1922. In Fig. 1 I have shown diagrammatically the apparatus there claimed in which a roller 10 has a series of longitudinally extending knives or cutters acting against appropriate faces on a roller 11 to form a series of transverse slits H corresponding to the side edges of 40 the slots or openings which are to be formed. The sheet, after passing between these rollers, passes between a second pair 12, 13, which act to form longitudinal slits K connecting the ends of the slits H of each pair 45 to circumscribe small waste portions which are removed on the roller 13 and taken from the latter by strippers 14. Thus the slots or openings B and B' are produced. The sheet then passes between feed rolls 15, 16, 50 a traveling chopper or cut off mechanism including coacting knives 17 and 18, then between feed rollers 19, 20, then rotary slitters 21, 22, and then to a conveyor or delivery mechanism 23. The chopper or cut off mechanism 55 is so designed as to form transverse cuts to separate the sheet into sections D and to travel with the sheet during the cutting action, so that the sheet may be continuously delivered at uniform and comparatively high 60 speed.

Having thus described my invention, what I claim as new and desire to secure by Letters Patent is:—

1. The method of forming a plurality 65 of non-symmetrical substantially identical

shingle strips, each strip having a row of tabs or projections along one longitudinal edge and of uniform width and adapted to simulate individual shingles and separated by open-ended slots, one of said tabs or projections having a side edge at one end edge of the strip and one of said slots being open at its side at the other end of the strip, which method consists in performing in a suitable order the steps of slotting the sheet, 75 slitting it lengthwise and cutting it transversely, the distance between the longitudinal slits being equal to the width of the strip, the distance between the transverse cuts being equal to the length of the strip, 80 each transverse cut being straight and extending the full width of the sheet and the slots being so positioned transversely of the sheet that each slot has one end registering with a lengthwise slit in the sheet and the 85 slots being so positioned lengthwise of the sheet that one or more of the slots lie at one side of and open into a transverse cut and one or more other slots lie at the opposite side of and open into the same transverse 90 cut.

2. The method of forming a plurality of non-symmetrical substantially identical shingle strips, each strip having a row of tabs or projections along one longitudinal edge and of uniform width and adapted to simulate individual shingles and separated by open-ended slots, one of said tabs or projections having a side edge at one end edge of the strip and one of said slots being open 100 at its side at the other end of the strip, which method consists in performing in a suitable order the steps of slotting the sheet, slitting it lengthwise and cutting it transversely, the distance between the longitudinal slits being equal to the width of the strip, the distance between the transverse 105 cuts being equal to the length of the strip, each transverse cut being straight and extending the full width of the sheet and all 110 of the slots being so positioned transversely of the sheet that each slot has one end registering with a lengthwise slit in the sheet and the slots being so positioned lengthwise of the sheet that each transverse cut registers 115 with one side edge of each of a plurality of slots, certain of the slots lying at one side of the cut and the remainder at the other side.

3. The method of forming a plurality of non-symmetrical substantially identical shingle strips, each strip having a row of tabs or projections along one longitudinal edge and of uniform width, and adapted to simulate individual shingles, and separated by open-ended slots, one of said tabs or projections having a side edge at one end edge of the strip and one of said slots being open at its side at the other end of the strip, which method includes forming in the sheet 120

slots arranged in a plurality of rows lengthwise of the sheet and rows transversely of the sheet, each longitudinal row being straight with the slots uniformly spaced, and each transverse row having one or more of the slots on one side of a line at right angles to the longitudinal rows and the remainder on the other side of said line, but each of the slots in the transverse row having one side edge registering with said line.

4. The method of forming a plurality of non-symmetrical substantially identical shingle strips, each strip having a row of tabs or projections along one longitudinal edge and of uniform width and adapted to simulate individual shingles and separated by open-ended slots, one of said tabs or projections having a side edge at one end edge of the strip and one of said slots being open at its side at the other end of the strip, which method includes forming in the sheet slots arranged in a plurality of rows lengthwise of the sheet and rows transversely of the sheet, each longitudinal row being straight with the slots uniformly spaced, and each transverse row having one or more of the slots on one side of a line at right angles to the longitudinal rows and the remainder on the other side of said line, but each of the slots in the transverse row having one side edge registering with said line, slitting the sheet lengthwise along lines intersecting each longitudinal row of slots at one end of each slot in the row, and cutting the sheet transversely along certain of the said lines at right angles to the longitudinal rows.

5. The method of making shingle simulating strips of flexible material for roofing purposes, consisting in providing a sheet sufficiently wide to make two or more strips, cutting a plurality of rows of openings in said sheet, said rows extending lengthwise of the sheet and said openings extending transversely of the sheet and spaced at uniform distances apart in all of said rows, the openings in one or more of said rows being out of transverse alignment with the openings of the other rows to a distance equal to the width of an opening and cutting said sheet transversely and longitudinally along straight lines, the transverse lines registering with one side edge of certain of the openings in the first mentioned rows and with the opposite side edge of the corresponding openings in the other row.

6. The method of making shingle simulating strips of flexible material for roofing purposes, consisting in providing a sheet sufficiently wide to make two or more strips, cutting a plurality of rows of openings in said sheet, said rows extending lengthwise of the sheet and said openings extending transversely of the sheet and spaced at uniform

distances apart in all of said rows, the openings in one or more of said rows being out of transverse alignment with the openings of the other rows to a distance equal to the width of an opening, and cutting said sheet transversely along straight lines registering with one side edge of certain of the openings in the first mentioned rows and with the opposite side edge of the corresponding openings in the other row, and slitting the cut off sections along lines registering with the ends of the openings of said rows.

7. The method of making shingle simulating strips of flexible material for roofing purposes which consists in forming in a sheet of flexible material transversely extending slots uniformly spaced apart in a row longitudinally of the sheet, forming a second row of similar slots, each slot of the second row being displaced from a corresponding slot of the first row lengthwise of the sheet to a distance equal to the width of a slot and transversely of the sheet to a distance equal to the length of the slot, whereby each slot of one row has one corner thereof coincident with one corner of a slot in the other row, cutting the sheet lengthwise along the line of said corners and transversely through certain of said corners.

8. The method of forming from a blank a plurality of shingle strips each when completed having notches opening out through one of its lengthwise edges and spaced apart to form intermediate portions simulating individual shingles, one of said shingle simulating portions of each strip having its side edge in alignment with the end of the strip, and one of said notches opening out at the opposite end of the strip, said method including forming in said blank substantially rectangular, transversely extending slots in two rows and spaced to uniform distances in both rows, each slot in one row having one corner substantially coincident with one corner of a slot in the other row, and cutting said sheet along a longitudinal line defined by said corners and along transverse lines intersecting certain of said corners.

9. The method of forming from a blank a plurality of shingle strips each when completed having notches opening out through one of its lengthwise edges and spaced apart to form intermediate portions simulating individual shingles, one of said shingle simulating portions of each strip having its side edge in alignment with the end of the strip, and one of said notches opening out at the opposite end of the strip, said method consisting in performing in a suitable order the steps of slotting the sheet, cutting it lengthwise into strips and cutting it transversely into sections, the step of slotting the sheet including forming in the blank substantially rectangular transversely extend-

ing slots in two rows and spaced to uniform distances in both rows, each slot in one row having one corner substantially coincident with one corner of a slot in the other row, 5 and the transverse and longitudinal cuts being so positioned that the longitudinal cut extends along the line defined by said cor-

ners and the transverse cuts are at uniform distances apart and intersect certain only of said corners.

Signed at New York in the county of New York and State of New York this 29th day of May A. D. 1922.

SAMUEL M. LANGSTON.
